UNITED STATES PATENT OFFICE.

PETER J. ARBES, OF ADA, MINNESOTA.

PANTS PRESSER.

Application filed July 25, 1922. Serial No. 577,413.

To all whom it may concern:

Be it known that I, PETER J. ARBES, a citizen of the United States, residing at Ada, in the county of Norman and State of Minnesota, have invented certain new and useful Improvements in Pants Pressers, of which the following is a specification.

This invention relates to a pants presser and has for its principal object to provide 10 a simple device of the character specified whereby the trousers may be pressed while hanging in any suitable place, and wherein the trousers are kept in a creased condition and free from any dirt.

15 Another object of the invention is to provide a pants presser of the above mentioned character whereby the trousers which are placed in the presser are adapted to be creased and furthermore having the pants 20 presser provided with cutout portions for receiving the cuffs of the trousers and also the seams thereof.

A still further object of the invention is to provide a pants presser of the above mentioned character, which is simple in construction, inexpensive in its manufacture, 25 strong and durable.

Other objects and advantages of this invention will become apparent during the 30 course of the following description.

In the accompanying drawings forming a part of this specification and which like numerals designate like parts throughout the same,

35 Figure 1 is a front elevation showing the pants presser in its open position,

Figure 2 is a perspective view of pants presser in its closed position, and

40 Figure 3 is a sectional view taken on line 3—3 of Figure 1, looking in the direction of the arrows.

In the drawings wherein for the purpose of illustration is shown the preferred embodiment of my invention, the numerals 45 1 and 2 designate a pair of oppositely disposed presser boards which are formed of any suitable material desired. The presser boards 1 and 2 have their inner edges arranged parallel to each other and are hinged- 50 ly connected to each other by means of suitable hinge members 3. The outer edges of the presser boards 1 and 2 are tapered as indicated by the numerals 4 and 5 in Figures 1 and 2 of the drawings and the purpose of 55 having the outer edges of the presser boards tapered is to conform to the tapered shape

of the trouser legs when the same are placed between the presser boards 1 and 2 for the purpose of creasing and folding the same. The presser board 1 has its tapered outer 60 edge 4 provided with outwardly projecting lugs 6 and arranged on the tapered portion 5 of the oppositely disposed presser board 2 are strap elements 7 which are provided for a purpose of engaging the outwardly 65 projecting lugs 6 formed on the tapered outer edge 4 of the presser board 1 whereby the presser boards 1 and 2 respectively are kept in a clamped position when the trousers are inserted therebetween. The 70 strap elements 7 are provided with apertured eyes 8 whereby the same may readily fit upon the outwardly projecting lugs 6. Furthermore they are of a spring like material so that they may be easily snapped 75 into and out of engagement with the lugs 6. Any suitable number of these latching elements may be placed along the tapered edges 4 and 5 of the presser boards 1 and 2 and I do not wish to confine myself to 80 the number to be used for the reason that any suitable number which would readily clamp the presser boards together are sufficient for the purpose.

The upper edges 9 and 10 of the presser 85 boards 1 and 2 respectively are also provided with a similar locking means 6 and 7 as arranged on the tapered edges of the presser boards to further aid in holding the presser boards in a clamped position. In order that the presser boards 1 and 2 when in use may be easily suspended suitable suspending means 11 is provided in the upper edge 9 of the presser board 1 whereby the pants presser may be placed upon any suitable support in order that the trousers may hang in a suspended position. The presser boards 1 and 2 are provided adjacent their edges 9 and 10 with transversely arranged inwardly opening receiving portions 12 and 13 respectively. The purpose of these transverse grooves 12 and 13 will be hereinafter fully described. Also provided on the inner faces of the presser boards 1 and 2 are the longitudinally extending grooves or cut out portions 14 and 15 respectively and these grooves 14 and 15 which are formed in the presser boards 1 and 2 respectively extend into the transverse grooves 12 and 13. 100 105

The purpose of the above mentioned 110 grooves is to allow the trousers when placed between the presser boards 1 and 2 to have

the cuffs thereof resting within the grooves 12 and 13 and the seams of the trousers when folded together lying within the grooves 14 and 15 formed in the presser boards 1 and 2 whereby the pressing of the trousers may be more readily and more efficiently done.

In use, the presser boards are placed in an open position as shown in Figure 1 and the trousers are folded in such a manner that 10 the trouser legs are placed upon one of the presser boards 1 and 2 whereby the cuffs of the trousers to be pressed are adapted to rest within the groove 12 or 13 and the seams of the trousers will lie in the longitudinally 15 extending grooves 14 or 15. The presser boards are then clamped together and held in a clamped positions by means of the straps 7 engaging the lugs 6 and the pants presser is then supported in any suitable place by 20 means of the suspension hook 11 and allowed to be suspended there for a suitable length of time. After the trousers have been allowed to remain between the presser boards for a suitable length of time the presser 25 boards are then opened and the trousers removed and it will thus be seen that the trousers are in condition for wearing and a well formed crease is obtained in the trousers without the appearance of any shine or gloss 30 thereon which would be apparent if an iron or other heated instrument was used in pressing the trousers.

It will be seen from the foregoing description that an easy and efficient method 35 has been obtained whereby a pair of trousers can be easily and quickly creased without the necessity of going to considerable expense and furthermore providing a device which is at hand at all times.

It is to be understood that the form of 40 my invention herewith shown and described is to be taken as the preferred embodiment of the same, and that various changes in the shape, size and arrangement of parts may be resorted to without departing from the 45 spirit of the invention or the scope of the subjoined claim.

Having thus described my invention what 50 I claim as new and desire to secure by Letters Patent is:—

As a new article of manufacture, a combined presser and casing for trousers comprising a pair of like companion presser boards oppositely disposed arranged to receive and completely house a pair of trousers, said presser boards having their inner longitudinal edges parallel to each other and hingedly connected, their outer edges being tapered toward one end, means connecting the boards together opposite to the point of 60 their hinge connection, the meeting face of each of the presser boards having transversely disposed grooves formed therein adjacent to the mentioned end thereof for receiving the cuffs of a pair of trousers, said 65 presser boards having their meeting faces also provided with straight longitudinally extending grooves adjacent to their straight longitudinal edges communicating with the transverse grooves for receiving the seams 70 of the trousers.

In testimony whereof I affix my signature in presence of two witnesses.

PETER J. ARBES.
